METAL UNDERBODY CONSTRUCTION

Ludwig G. Boehner, Rehbrucke, near Potsdam, Germany, assignor to General Motors Corporation, Detroit, Mich., a corporation of Delaware

Application June 13, 1936, Serial No. 85,023
In Germany November 9, 1935

13 Claims. (Cl. 280—106)

The invention relates to the construction of a sub-frame combining in a single unit the structure of the usual chassis and body underframe. In the prior art the advantages of a common frame as well as the difficulties in the production of such a frame are recognized, but it is believed desirable to repeat that the essential advantages of the common frame consist in its light weight and its low center of gravity, while the difficulties 5 in construction arise from the fact that the front part of the sub-frame (which carries the engine) must be made much narrower than the middle part. The middle part must have the same width as the body because only in having a wide 10 middle is it possible to build a short and easily steered car without limiting the space for the passengers. If the front part of the sub-frame is greatly narrowed, the stiffness, not only of the sub-frame but also of the entire frame, suffers 15 to an extraordinary degree. According to the prior methods of construction of unitary chassis and body frames, a weakening of the moments of resistance of the different girders or parts has been compensated by an increase in weight or 20 thickness of metal. But this method takes from the unitary frame one of its main advantages, namely, low weight. Thus, the problem arises of compensating for the small degree of stiffness 25 of the sub-frame, caused by the narrowing of the front part of the sub-frame, by a thorough detailed study of the design of the sub-frame. The redesigned frame must not increase the weight of 30 the unitary sub-frame as compared with the prior art frame that has not been narrowed.

35 In the prior art solutions are given for the production of a sub-frame which is stiffened against distortion, bending and shifting. The basis of these solutions has been the idea of making the frame out of a large number of small and simple 40 iron shapes, in order to save large and expensive dies and presses. While the production of the separate parts was thus made simple and cheap, the assembly of the sub-frame, however, on account of the multiplicity of the parts, remained 45 comparatively expensive. According to the present invention, in order to simplify and cheapen the assembly, instead of the many small parts of the prior art a few large pressed parts are used 50 for the construction of the sub-frame. On the other hand, in order not to cause excessive increase in the cost of presses, the number of the large pressed parts required is held as low as possible and sub-frames that are stiffened against 55 bending, distortion and shifting are produced

merely by the form that is given to the pressed parts.

According to the invention the middle frame portion of the sub-frame, that is, that part which has the same width as the body, is constructed 5 substantially of two pressed sheets which are formed at their edges into a channel or a U-shaped profile. The sheets are laid on each other and welded together in such a way that the U-shaped parts of the two sheets mate 10 and form at the edge of the frame a box-shaped girder of high resistant properties. On account of the low center of gravity of the body, a tunnel 15 for the propeller shaft is necessary, and transverse walls placed at right angles to this tunnel are 20 connected with the tunnel and the sheet metal frame in order to increase the rigidity of the frame against torsion. In the construction of the new sub-frame special consideration has been 25 given to making the lower side of the frame as smooth as possible, the purpose of this structure being to obtain a favorable airflow or decrease in air resistance. Care has also been taken to keep the ground clearance low by avoiding having any parts projecting downward from the sub-frame. 30 Moreover, the frame is constructed in such a way that dust, water or mud cannot penetrate into the body.

On the drawings

Figure 1 is a plan view of the sub-frame. 30
Figure 2 is a side view.

Figures 3, 4, and 5 are longitudinal sections 35 through the sub-frame on the lines 3—3, 4—4, and 5—5 of Figure 1.

Figures 6 to 9 inclusive are transverse sections 40 through the sub-frame on the lines 6—6, 7—7, 8—8, and 9—9 of Figure 1.

Figures 10, 11, and 12 are transverse sections 45 through the sub-frame on the lines 10—10, 11—11, and 12—12 of Figure 3.

Figures 13 and 14 are transverse sections 50 through the sub-frame on the lines 13—13 and 14—14 of Figure 1.

Figure 15 is a longitudinal section on line 55 15—15 of Figure 1.

Figure 16 is a perspective view of the sub-frame, seen from above.

As already indicated, the middle part of the sub-frame consists of a lower sheet 1 and an upper sheet 2. As is apparent from the detailed 50 cross sectional views in Figures 6, 7, 8, and 9, the lower pressing 1 has pressed out or formed along its longitudinal edges a U-shaped profile or channel 3 which decreases in depth from rear to front. The upper sheet 2 consists of two 55

wings 2a and 2b, which have a U-shaped profile or channel 4 running around their edges and formed by stamping or pressing. The sheet 2 has a central cut-out which forms the wings, 5 and where the wing edges face each other on the longitudinal center line of the car no channels are provided. The channel 3 has the lateral flange 3a and the channel 4 has the lateral flange 4a mating with the flange 3a and welded 10 thereto.

As shown in Figure 1, both the upper and the lower sheets are indented at the front end at the middle as shown at A in order to provide a free or an open space for the mounting of the engine 15 block. At this point the U-shaped sections of the two portions 2a and 2b of the sheet are integral and combine into a single profile 5 which extends inwardly of the frame and ends at the first transverse bracing 17 of the frame.

20 From the end of the profile 5 and rearwardly of the bracing 17, the edges of the two sheets 2a and 2b are bent upwardly as at 6 and then inwardly flanged as at 6a, the flanges being connected throughout their entire length to complementary flanges 7a of an arched tunnel 7 to form a box section, so that a box girder with high resistance properties is produced at the middle of the frame. As is shown in Figures 1 and 4, the tunnel 7 is welded at its front end 25 at 7b to the profile 5 and at its rear end to the adjacent parts of the frame. Where the U-shaped profiles of the upper sheets are not made into a box girder by a corresponding U-shaped profile of the lower sheet, the same effect is accomplished by the flat lower sheet itself. The result is that the middle part of the frame consists of three longitudinal girders, that is, the two girders 3-4 at the sides and the tunnel 7, and two transverse girders of box section, that 30 is, the girders 3-4 at the ends.

40 As is seen from the cross sectional view, the profile 4 of the upper sheet 2 is deeper than the profile 3 of the lower sheet 1. In order to obtain a better flowing of the material in the pressing 45 of the sheets 2a and 2b, rectangular pieces 8 are cut out of the upper sheet; at these points the lower sheet which now has to carry all the load, is stiffened by beads 8a.

The longitudinal extension girders 9 of the 50 front part of the frame pass through the box section formed by the channel or profile 4 in the wings 2a and 2b at the front end of the frame. These girders taper or become smaller gradually toward the rear. Beyond the place 55 of entry of the girders 9, U-shaped profiles 10, gradually tapering or decreasing in height toward the rear, are pressed out of the sheets 2a and 2b. These channels 10 run parallel with the longitudinal axis of the frame and are connected with the profile 4 and form shoes for the 60 reception of the longitudinal girders 9 which are welded thereto. The lower sheet 1, where the girders 9 pass, is cut away to receive the girders and the edges 9a at the cut-away part welded 65 to the flanges 9b of the girders. If desired, channels corresponding to the channels 10 may be pressed upwardly from the sheet 1 into the channels 10 to form the shoe for the girders.

The longitudinal girder 9 at its foremost part 70 has an open box-shape (Figure 10). Then, as is seen from Figures 2 and 11, a sheet 11 is welded to the under side of the girder. A short distance from the girder end the sheet 11 takes a U-shaped profile (Figure 12) and is welded to the flanges 75 70 of the longitudinal girder 9 and produces a box-

shaped profile of high resistance properties. A plate 11a is preferably placed between the upper and lower channels of the girder 9 the plate commencing immediately before the girder 9 enters the channel 4 and ending at the end of the girder. 5

Figure 1 shows how the forces are transmitted from the front frame to the middle part of the frame. It is essential that the forces which pass from the middle part of the frame to the rear part of the frame and then to the rear axle, be offered further resistance, that is, it is desirable that the rear part of the frame, as far as possible, be given rigidity to resist bending and torsion. The fulfilling of this requirement at the rear part of the frame offers constructional difficulties for the 15 reason that the low position of the middle part of the frame with relation to the axles of the car makes it necessary to curve the frame upward or provide it with a kick-up, so that it may extend up over the axle. 20

The rear part of the frame consists of an arched sheet 12 (Figure 5) which forms a continuation of sheet 1 and has a deep channel or U-shaped profile 12a at its rear and lateral edges. By means of the channel or U-shaped profiles 13 25 the profiles 12a are supplemented in such a way as to make welded closed box girders. The height of the channel or profile 13 decreases gradually toward the rear of the frame. At the rear end of the frame the channel 12a is welded to a cover 30 plate 14. Intermediate its length at a plurality of points the rear sheet 12 is provided with transverse channels or ribs 12b (Figures 5, 14, and 15) which are covered by channel strips 12c welded thereto to form box sections. At the edge of the 35 sheet 12 the strips 12c are flattened as at 12d and the flat end welded between the channels 12a and 13. Additional pressings 12e and 12f may be provided for strengthening purposes.

The channels 13 are divided or forked at the 40 front end into two channels 13a and 13b, connected by the strengthening ribs 13c and the flat part 13d. The channel 13a follows the channel 12a while the channel 13b is directed inwardly and is welded to the sheet 12, while a channel rib 45 13f formed in the sheet 12 mates with the ribs 13c to form a box-sectioned construction. The sheet 12, the channels 12a, as well as the channels 13a and 13b are lap-welded to the sheets 1 and 2 and to the channels 3 and 4, the lap welds being 50 coincident with the points where the front ends of the rear springs are attached. The lapping gives the great strength necessary at this point. 55

Bosses 15 are pressed downward in the sheet 12 below the position for the rear seat, and between them there is an arched part 16 which is lap welded at 16a to the rear end of tunnel 7. This connection 16a increases the stiffness of the 60 rear part of the frame and of the sub-frame as a whole to a very considerable degree.

The above description of the sub-frame shows the passage of the forces or the transmission of the forces to the rear part of the frame or vice versa. Shocks occurring in collisions are transmitted from the longitudinal members 9 to the box-shaped edge girders and to the tunnel 7, and then to the rear longitudinal girders 12a-13, the transmission of the forces being effected or transmitted from the tunnel through the channels 13b 70 which extend over toward the tunnel. Forces acting vertically downward and combined at the center of the frame are transmitted through the box-shaped edge girders and through the tunnel made in the form of a girder, either directly or 75

through the vehicle body to the points where the springs are attached.

In order to make the sub-frame rigid, not only against bending and displacement or shifting but fully resistant to torsion as well, several additional transverse girders are added. Near the front end of the middle part of the frame there is a transverse rib and front seat support 11, which is made by welding together two Z-shaped sheets 11a and 11b. The bottom flanges of the members 11a and 11b are welded to the sheets 2a and 2b, to the channels 4, and to the tunnel 7 in such a way that the transverse rib 11 is given a closed box-shaped section of high resistance properties. The rib 11 is highest at the middle where it passes over the tunnel 7 and tapers gradually towards both ends where it has substantially the same height as the channel 4. As shown in Figures 3 and 4, the sheet is carried over the tunnel 7, so that a continuous flow of forces may be transmitted in the transverse direction of the frame. The same idea is carried out in the other transverse stiffening members. Immediately below the rib 11 the sheet 2 is provided with a rib 11c. Also the heel plate and rear seat support 18 in the rear has been given a box-shaped profile, the flanges 18c of which are welded to the upper sheets 2a and 2b, to the channel 4 and to the tunnel 7. The heel plate 18 comprises the channel member 18a and the arch 18b welded to each other and to the adjacent parts. Here also the sheet is carried over the tunnel 7 in order to prevent any interruption in the transmission of forces. At the heel plate ends triangular flanged plates 18d are welded by their flanges to the plate ends and to the channels 13b. If desired, these plates 18d may be the bent-over ends of the channel member 18a. Pressed or indented portions 18e to stiffen the channel 18a may optionally be used. The same idea is found also in the semi-circular rib 19 formed in the upper sheets 2a and 2b at the middle part of the frame. As shown in Figures 4 and 8, the sheets 1 and 2 have parts at their middle cut for the width of the tunnel, but in order to obtain an uninterrupted transmission of forces for the transverse stiffening 19, a semi-circular sheet 20 is welded below to bridge the break caused by the tunnel.

The lower sheet 1 is downwardly arched at its rear end under the tunnel as shown at 22 in Figures 2 and 4 to accommodate the propeller shaft. The rearmost part of the sheet 1 under the tunnel is split at its middle and flanged upwardly against the tunnel as shown at 23 in Figures 4 and 9.

I claim:

1. A unitary vehicle frame combining the chassis and the underframe of the body, said unitary frame consisting of a middle part the width of the vehicle body, a narrowed front part, and an arched rear part, said middle part comprising upper and lower sheets, a U-shaped profile or channel formed at the edge of each sheet, said sheets being welded together, said channels mating with each other to form a box-shaped girder at the edge of the frame, said upper sheet consisting of two wing parts having a space therebetween, upwardly flanged inner edges on said wings, and a tunnel welded to said flanges to form a box-shaped girder.

2. A unitary vehicle frame combining the chassis and the underframe of the body, said unitary frame consisting of a middle part the width of the vehicle body, a narrowed front part, and an arched rear part, said middle part com-

prising substantially two sheets, a U-shaped profile or channel formed at the edge of each sheet, said sheets being welded together, said channels mating with each other to form a box-shaped girder at the edge of the frame, and a tunnel centrally of the frame and welded to the wide part of the frame to form therewith a box-sectioned construction.

3. A unitary vehicle frame combining the chassis and the underframe of the body, said unitary frame consisting of a middle part the width of the vehicle body, a narrowed front part, and an arched rear part, said middle part comprising substantially two sheets, a U-shaped profile or channel formed at the lateral edge of each sheet, said sheets being welded together, said channels mating with each other to form a box-shaped girder at the edge of the frame, said two sheets being indented at the front end at the right and left of the center line, U-shaped profiles or channels in the upper sheet at the indented edge, said lower sheet being flat at the front edge and closing the front edge channel to form a box-shaped section.

4. A unitary vehicle frame combining the chassis and the underframe of the body, said unitary frame consisting of a middle part the width of the vehicle body, a narrowed front part, and an arched rear part, said middle part comprising substantially two sheets, a U-shaped profile or channel formed at the lateral edge of each sheet, said sheets being welded together, said channels mating with each other to form a box-shaped girder at the edge of the frame, longitudinal girders forming the front narrow part of the frame, U-shaped profiles or channels at the front end of the middle part of the frame, said last-named channels having openings, and U-shaped profiles of decreasing height pressed out of the upper sheet and forming shoes for the ends of the longitudinal girders, said girders being welded in said shoes.

5. A unitary vehicle frame combining the chassis and the underframe of the body, said unitary frame consisting of a middle part the width of the vehicle body, a narrowed front part, and an arched rear part, said middle part comprising substantially two sheets, a U-shaped profile or channel formed at the edge of each sheet, said sheets being welded together, said channels mating with each other to form a box-shaped girder at the edge of the frame, said rear part of the frame consisting of an arched sheet, U-shaped profiles or channels at the edges of said arched rear sheet, channels at the longitudinal edges of the arched sheet mating with the channels thereof to form box-shaped girders at the longitudinal edges of the sheets.

6. A unitary vehicle frame combining the chassis and the underframe of the body, said unitary frame consisting of a middle part the width of the vehicle body, a narrowed front part, and an arched rear part, said middle part comprising substantially two sheets, a U-shaped profile or channel formed at the edge of each sheet, said sheets being welded together, said channels mating with each other to form a box-shaped girder at the edge of the frame, said rear part of the frame consisting of an arched sheet, U-shaped profiles or channels at the edges of said arched sheet, channels at the longitudinal sides of the arched sheet welded to and mating with channels thereof to form box-shaped girders at the longitudinal edges of the sheets, said channels at the longitudinal edges of the arched sheet being

- forked into two branches, a central longitudinal tunnel, one arm of the fork extending in the direction of the tunnel, the other arm being welded to the U-shaped profiles of the upper sheet.
5. 7. A unitary vehicle frame combining the chassis and the underframe of the body, said unitary frame consisting of a middle part the width of the vehicle body, a narrowed front part, and an arched rear part, said middle part comprising 10 substantially two sheets, a U-shaped profile or channel formed at the edge of each sheet, said sheets being welded together, said channels mating with each other to form a box-shaped girder at the edge of the frame, said rear part of the 15 frame consisting of an arched sheet, U-shaped profiles or channels at the edges of said arched sheet, channels at the longitudinal sides of the arched sheet mating with and welded to the channels thereof to form box-shaped girders at the 20 longitudinal edges of the sheets, the connection between the middle part of the frame and the arched rear sheet being effected by lapping and welding at the points on the frame at which the rear springs are connected.
25. 8. A unitary vehicle frame combining the chassis and the underframe of the body, said unitary frame consisting of a middle part the width of the vehicle body, a narrowed front part, and an arched rear part, said middle part comprising 30 substantially two sheets, a U-shaped profile or channel formed at the edge of each sheet, said sheets being welded together, said channels mating with each other to form a box-shaped girder at the edge of the frame, a tunnel welded to the 35 middle part of the frame, said rear part of the frame consisting of an arched sheet, U-shaped profiles or channels at the edges of said arched sheet, channels at the longitudinal edges of the arched sheet mating with and welded to the channels thereof to form box-shaped girders at the 40 longitudinal edges of the sheets, said sheet being arched downward at its sides under the seat and arched upward substantially on the center line of the car between the seats, said arch conforming 45 in shape to the profile of the tunnel and welded to the tunnel.
9. A unitary vehicle frame combining the chassis and the underframe of the body, said unitary frame consisting of a middle part the width of the 50 vehicle body, a narrowed front part, and an arched rear part, said middle part comprising substantially two sheets, a U-shaped profile or channel formed at the edge of each sheet, said sheets being welded together, said channels mating with 55 each other to form a box-shaped girder at the edge of the frame, a tunnel at the center of the frame, a transverse brace at the middle part of the frame, said transverse brace being secured to the upper of the two sheets and to the tunnel to 60 form a box-shaped cross sectional construction,

said transverse brace extending above the tunnel.

10. A unitary vehicle frame combining the chassis and the underframe of the body, said unitary frame consisting of a middle part the width of the vehicle body, a narrowed front part, and an arched rear part, said middle part comprising 5 substantially two sheets, a U-shaped profile or channel formed at the edge of each sheet, said sheets being welded together, said channels mating with each other to form a box-shaped girder 10 at the edge of the frame, stiffening arches formed in the individual sheets of the middle part of the frame, said sheets having a cut-out part, a tunnel bridging the upper side of the cut-out part, and formed sheets bridging the break in the cut- 15 out from below.

11. In a unitary vehicle frame combining the chassis and the underframe of the body, said frame consisting of a middle part, a front part and a rear part, said middle part comprising a 20 plurality of metal sheets secured together, mating upwardly and downwardly directed channels on the sheets to form box girder constructions at the edges of the sheets, a box girder construction at the front edge of the sheets, transverse bracing means to reinforce the sheets, a longitudinal tunnel secured to the middle of the frame, a plurality of transverse braces welded to the middle frame part, said braces secured to and extending 25 over the tunnel.

12. In a unitary vehicle frame combining the chassis and the underframe of the body, said frame consisting of a middle part, a front part and a rear part, said middle part comprising a 30 plurality of metal sheets secured together, mating upwardly and downwardly directed channels on the sheets to form box girder constructions at the edges of the sheets, a transverse brace at the forward part of the middle frame part, and a transverse brace at the rear of the middle frame 35 part, said transverse braces extending the full width of the frame and being welded thereto.

13. In a unitary vehicle frame combining the chassis and the underframe of the body, said frame consisting of a middle part, a front part 45 and a rear part, said middle part comprising a plurality of metal sheets secured together, mating upwardly and downwardly directed channels on the sheets to form box girder constructions at the edges of the sheets, a transverse brace at the 50 forward part of the middle frame part, a transverse brace at the rear of the middle frame part, transverse braces extending the full width of the frame and being welded thereto, and a channel formed in the upper sheet between the two trans- 55 verse braces and extending transversely of the frame and being closed at its underside by the lower sheet.

LUDWIG G. BOEHNER. 60

CERTIFICATE OF CORRECTION.

Patent No. 2,126,607.

August 9, 1938.

LUDWIG G. BOEHNER.

It is hereby certified that error appears in the printed specification of the above numbered patent requiring correction as follows: Page 3, first column, line 44, after the word "cut" insert out; page 4, second column, line 53, claim 13, before "transverse" insert said; and that the said Letters Patent should be read with this correction therein that the same may conform to the record of the case in the Patent Office.

Signed and sealed this 25th day of October, A. D. 1938.

Henry Van Arsdale
